STOOL

Oscar C. Blomgren, Winnetka, Ill.

Application June 20, 1942, Serial No. 447,752

6 Claims. (Cl. 155—150)

The invention relates to an article of furniture and has particular reference to a stool of general utility that can be constructed entirely of wood or entirely of metal or a combination of both and one that can be easily assembled and disassembled.

An object of the invention is to provide a stool having a plurality of legs angularly arranged with respect to each other and which can be easily assembled, requiring the minimum of parts in its construction and which will maintain itself in assembled relation without the use of glue or like fastening means.

A further object of the invention is to provide a three legged stool of general utility, having novel fastening means for the legs and which will maintain all the parts in assembled relation while at the same time making it possible to readily remove the legs from the fastening means and disassemble the stool in its entirety.

Another object is to provide an article of furniture having a plurality of legs angularly arranged with respect to each other and releasably held in assembled position by wedge members which when in operative associated relation form a unit of attractive appearance so as not to detract from the decorative appearance of the article as a piece of furniture.

Another object of the invention is to provide an article of furniture having a plurality of angularly arranged legs and spaced wedge members for retaining the article in assembled relation, the wedge members being located at the point where the legs have the minimum spread and where said legs cross with respect to each other.

A further object is to provide an article of furniture of simple construction that can be economically manufactured and which will comprise a minimum number of parts.

With these and other objects in view, the invention may consist of certain novel features of construction and operation as will be more fully described and particularly pointed out in the specification, drawings and claims appended hereto.

In the drawings, which illustrate an embodiment of the invention, and wherein like reference characters are used to designate like parts—

Figure 1 is a perspective view of one embodiment of the invention in the form of a three legged stool constructed in accordance with the invention;

Figure 2 is a perspective view showing the various parts of the stool in disassembled relation;

Figure 3 is a bottom plan view of the seat il-

lustrating the layout for locating the openings for the legs and for determining their angular positioning with respect to the center of the seat;

Figure 4 is a fragmentary sectional view taken vertically through the seat of the stool on line 4—4 of Figure 3, and showing one opening for receiving a leg;

Figure 5 is a plan view of a wedge member showing the three openings therein through which the legs extend and illustrating the manner of locating and orienting said openings;

Figure 6 is a side elevational view showing the two wedge members in proper contacting relation;

Figure 7 is a vertical sectional view taken on a diameter such as 7—7, Figure 5, and showing the two wedge members in spaced relation with resilient means located therebetween;

Figure 8 is a vertical sectional view similar to Figure 7 but showing another form of resilient means such as a rubber ball for applying tension to the members to maintain them in spaced apart relation; and

Figure 9 is a vertical sectional view similar to Figure 7 and showing in addition thereto a retaining bolt extending through the center of the wedge members for holding them in assembled relation as a unit.

In the drawings, particularly Figures 1 and 2, the invention is shown as embodied in a three-legged stool of general utility including a seat 10 of circular form and having a thickness sufficient for the purposes of the present invention but which is in keeping with the size of the stool so as to constitute a decorative as well as a practical element of the combination. The three legs 11, 12 and 13 are angularly arranged with respect to each other and said legs also have a very definite angular relation with the vertical. This angular

relation of the legs also determines that of the openings in the undersurface of the seat, as will be more particularly described, the said openings receiving the ends of the legs to thereby join these elements to the seat. The wedge members 14 and 15 comprise the sole retaining means for the present article of manufacture since the members function to hold the three legs and the seat in assembled relation. A feature of the present invention resides in the provision of the wedge members and the manner of holding them in spaced relation so as to apply tension to the legs, thus securely holding all the parts in their proper position while at the same time permitting disassembly of said parts by forcing the wedge members toward each other to relieve the tension on

the legs applied thereby. The wedge blocks are located at an intermediate point on the legs where the legs cross and in both an upward and downward direction it will be observed that the legs diverge with respect to each other. When the upper block 14 is forced upwardly and the lower block 15 is forced downwardly against the diverging legs a gripping action results with sufficient tension being applied to the parts to hold them in assembled relation and which tension increases in proportion to the force maintaining the blocks in separated relation. In Figure 2 the elements of the present stool are shown disassembled and it will be observed that in addition to the foregoing elements a coil spring 16 is used as the resilient means, having location between the wedge members for maintaining the same in spaced operative position.

The seat 10 comprises a circular piece of wood or metal or any other material suitable for a stool such as described, the same having the desired size and proper thickness. Three openings 17, 18 and 19 are bored in the undersurface of the seat at the desired angle and to the proper depth for receiving one end of the legs 11, 12 and 13, respectively. In the particular embodiment of stool disclosed in the drawings each opening is bored at an angle of twenty-eight degrees with respect to the vertical. This is better illustrated in Figure 4, which is a vertical sectional view taken through the seat on the center line of the leg for the express purpose of illustrating the angular position of a leg which forms the angle X with respect to the vertical, having a magnitude of twenty-eight degrees as shown in said figure. Also each of the legs 11, 12 and 13 has a very definite angular relation with each other which is best illustrated by referring to the layout shown in Figure 3. In this figure the three openings in the underside of the seat are shown in full lines and the legs are illustrated in dot and dash line which has been selected for clearness, since it will be observed that the projection of each leg on the seat partly overlies the opening for one of the other legs.

To determine the location of openings 17, 18 and 19 the circular seat 10 is divided into three equal parts by the radial lines A, B, C, which form with each other an angle of one hundred and twenty degrees, as will be clearly understood. An equilateral triangle including the sides D, E, F, is then laid out so that the apices of the triangle fall on the radial lines previously referred to. The apices of the triangle thus locate the center of the openings which are one hundred and twenty degrees apart. Whereas, each leg forms an angle of twenty-eight degrees with the vertical, the other angular positioning of the leg is only twenty-three and one-half degrees, as clearly evidenced in Figure 3. This is an angle which the center line of each leg, namely, 11, 12 and 13, forms with its respective radial lines A, B or C. More particularly the center line L for the leg 11 is disposed inwardly toward the center of the seat so as to form an angle of twenty-three and one-half degrees with its radial line A. In a similar manner the center line M for leg 12 forms an angle of twenty-three and one-half degrees with its radial line B. With respect to opening 19 the leg 13 has its center line N disposed at an angle of twenty-three and one-half degrees with its radial line C. With the bottom surface of the seat 10 laid out as above indicated the center of each of the openings 17, 18 and 19 is definitely located and the direction in which these openings are

bored is also ascertained. While maintaining an angle with the vertical of twenty-eight degrees each opening is bored into the block for the proper depth and in a manner to maintain an angle of twenty-three and one-half degrees with respect to its radial line. This angle is measured on the bottom surface of the seat and is the angle between the radial line and the axial center of the opening. When the legs are fitted into the openings and held in assembled relation by the wedge members said legs have the angular position as illustrated in Figure 1.

The function of the wedge members is to maintain the legs in assembled relation, provided the seat 10 has been properly fitted to the upper end of said legs. The circular blocks 14 and 15 are each bored with three openings, opening 21 being provided for receiving the leg 11, opening 22 for receiving the leg 12, and opening 23 for receiving the leg 13.

As a guide in determining the location of these openings the surface of each member is laid out as illustrated in Figure 5. An equilateral triangle having the sides R, S, T, is drawn on said surface and within the same a smaller triangle is drawn having sides U, V, W. The apices of the small interior triangle are located at the mid-point of the respective sides of the larger triangle and these points each forms the center for an opening. Said opening is bored through the member at an angle of twenty-eight degrees from the vertical and in a direction so that the axial center of the opening is parallel to one of the sides R, S, or T of the large equilateral triangle. The other wedge member 14 may be laid out in a similar manner and identical openings bored therethrough in the proper angular direction. When the two members are associated as in Figure 6 the openings 21, 22 and 23 in the top member 14 should coincide with their companion openings in the bottom member 15. The final result is that the unit formed by the two members will have three openings extending completely through the same of a diameter to receive the legs, and which openings will extend at the proper angle with respect to the vertical for accommodating said legs.

As previously explained, the legs of the present stool are held in assembled relation with the seat by tension applied by the wedge blocks 14 and 15 to said legs. Each wedge block is formed with a central cavity or recess 25 in its contacting surface for receiving the coil spring 16. The said spring acts to maintain the wedge blocks spaced and in so doing applies sufficient binding action to the legs to maintain them in assembled relation, it being understood that the legs are additionally held as a result of their insertion in openings provided therefor in the seat. Figure 7 illustrates the location of the resilient spring in the recesses 25 of the wedge blocks. In Figure 8 a modified construction is disclosed wherein the resilient spring 16 is replaced by a rubber ball 26 or the like. In Figure 9 a bolt 27 has been inserted through both the wedge blocks centrally thereof and therefore passes through the center of the resilient coil spring 16. The blocks are held in assembled relation by the nut 28 threaded to the lower projecting end of the bolt and as a result of this construction the wedge blocks at all times constitute a unit which can be assembled with the legs and disassembled therefrom without separating the blocks from each other. This precludes any possibility of losing the coil spring or of the same becoming misplaced as a result of disassembly of the stool.

In assembling the elements of the present stool it is necessary to press the two wedge blocks together compressing spring 16 so that the inner surfaces of the blocks are in contacting relation such as shown in Figure 6. In this position of the blocks the three openings extending through each are in alignment and the legs will have some freedom, permitting movement to the extent where the legs can be inserted in the openings in the seat and it is immaterial which leg is inserted in which opening since all three legs are identical in length and in diameter. After the seat has been applied, the legs entering the openings 17, 18 and 19 in the undersurface of the seat, the pressure is released with respect to the wedge blocks and they are allowed to separate under the action imparted thereto by the coil spring 16 or other resilient member. This separation of the blocks has a binding action with respect to the legs, or, in other words, may be considered as applying tension thereto, holding the legs rigid and in proper assembled relation.

After the stool has been assembled as above described it can be lifted and moved from place to place without any of the elements becoming separated. In fact, the weight of a person sitting on the stool further aids in the application of tension to the legs through the wedge blocks and thus tends to more securely bind the elements together as a unit. Since the legs are held together without the use of glue, screws or like fastening means, it is possible to readily disassemble the present stool since it is only necessary to compress the wedge blocks against the spring 16, whereupon the legs can be withdrawn and the various parts can then be separated as shown in Figure 2 to facilitate cleaning or for other purposes. The wedge blocks are located at the point where the legs have the minimum spread and where said legs cross with respect to each other. This is a necessary location for the blocks since the resilient spring which functions to maintain them separated forces one block upwardly against the spreading of the legs, whereas, the lower block is forced downwardly also against the spread of the legs in this direction. Notwithstanding the functional action of said blocks they also have an attractive appearance which adds to the decorative appearance of the stool as an article of furniture.

The openings 21, 22 and 23 in the wedge blocks have an angular relation which coincides with that of the legs at the horizontal plane where said legs cross each other and said openings are spaced so as to properly space the legs at this point. Any movement of the blocks in opposite directions produces a binding of the blocks on the legs and the parts are thus interlocked with each other and with the seat. The resilient spring 16 or other resilient means functions to maintain the blocks separated with one being located above the said horizontal plane and the other below the horizontal plane.

The invention is not to be limited to or by details of construction of the particular embodiment thereof illustrated by the drawings as various other forms of the device will of course be apparent to those skilled in the art without departing from the spirit of the invention or the scope of the claims.

What is claimed is:

1. An article of furniture, in combination, a seat, a plurality of legs for supporting the seat, said seat having openings in its undersurface for receiving the legs to join the same to the seat,

said openings being located an equal distance apart and extending diagonally with respect to the undersurface of the seat whereby the legs are diagonally arranged so that they cross each other intermediate their length, a plurality of members for maintaining the legs and seat in assembled relation, said members having openings through the same through which the legs extend, and said members having a location above and below a horizontal plane intermediate the length of the legs in which plane the legs cross each other, whereby movement of one member in an upward direction and movement of the other member in a downward direction applies gripping action to the legs to interlock the members therewith, and means maintaining the members in separated relation.

2. An article of furniture, in combination, a seat, a plurality of legs for supporting the seat, said seat having openings in its undersurface for receiving the legs to join the same to the seat and said legs being disposed at an angle to the vertical when the seat is supported horizontally, whereby said legs cross each other in the same horizontal plane intermediate the length of the legs, a plurality of members for maintaining the legs and seat in assembled relation, said members having openings through the same through which the legs extend, said members having a location above and below a horizontal plane respectively whereby movement of one member in an upward direction and movement of the other member in a downward direction applies tension to the legs to interlock the members therewith, and resilient means located between the members for yieldingly forcing the same in opposite directions.

3. An article of furniture, in combination, a substantially horizontal member providing a supporting surface, a plurality of legs for supporting the member, said legs having releasable interfitting relation with the member and said legs being disposed at an angle with respect to each other whereby said legs cross on the same horizontal plane intermediate the length of the legs, an upper and a lower wedge block, said wedge blocks each having a plurality of openings through the same through which the legs extend, one of said wedge blocks having a location above said horizontal plane and the other wedge block having a location below the horizontal plane, and resilient means located between the wedge blocks for maintaining them separated to thereby apply tension to the legs to hold the legs and seat in assembled relation.

4. An article of furniture, in combination, a substantially horizontal member providing a supporting surface, a plurality of angularly disposed legs for supporting the member, said legs having releasable interfitting relation with the member and being disposed at an angle with respect to each other whereby the legs cross on a horizontal plane intermediate the length of the legs, means located above and below said horizontal plane respectively for maintaining the legs and member in assembled relation, each said means having openings therethrough corresponding to the legs and through which the legs extend, and a resilient member located between the means for yieldingly holding the same in separated position.

5. An article of furniture, in combination, a substantially horizontal member providing a supporting surface, a plurality of legs for supporting the member, said legs having releasable interfitting relation with the member and said legs be-

ing disposed at an angle with respect to each other whereby said legs cross on the same horizontal plane intermediate the length of the legs, said legs flaring outwardly in directions above and below the horizontal plane, an upper and a lower wedge block having location above and below the plane respectively, each wedge block having openings through the same through which the legs extend, and which openings are angularly arranged to coincide with the angular relation of the legs at the horizontal plane, whereby upward movement of the upper wedge block and downward movement of the lower wedge block produces a gripping action on the legs as a result of the outward flare of the legs in the respective directions, and means maintaining said wedge blocks in separated relation.

6. An article of furniture, in combination, a substantially horizontal member providing a supporting surface, a plurality of legs for supporting the member, said legs having releasable interfit-

ting relation with the member and said legs being disposed at an angle with respect to each other whereby said legs cross on the same horizontal plane intermediate the length of the legs, said legs flaring outwardly in directions above and below the horizontal plane, an upper and a lower wedge block having location above and below the plane respectively, each wedge block having openings through the same through which the legs extend, and which openings are angularly arranged to coincide with the angular relation of the legs at the horizontal plane, whereby upward movement of the upper wedge block and downward movement of the lower wedge block produces a gripping action on the legs as a result of the outward flare of the legs in the respective directions, and means located between the wedge blocks for yieldingly forcing the blocks in opposite directions.

OSCAR C. BLOMGREN.
